UNITED STATES PATENT OFFICE.

HENRY FROEHLING, OF RICHMOND, VIRGINIA.

APPARATUS FOR MIXING WET AND DRY CEMENT MATERIALS.

SPECIFICATION forming part of Letters Patent No. 495,323, dated April 11, 1893.

Application filed April 7, 1892. Serial No. 428,192. (No model.)

To all whom it may concern:

Be it known that I, HENRY FROEHLING, of Richmond, in the county of Henrico, in the State of Virginia, have invented new and useful Improvements in Processes of and Apparatus for Mixing Materials for Making Portland Cement and for other Purposes, of which the following, taken in connection with the accompanying drawings, is a full, clear, and exact description.

My invention relates to machinery and apparatus for mixing wet or dry materials by a continuous process creating a homogeneous compound, whether the materials are of equal or varying proportions.

My object, primarily, is to produce an improved process and apparatus for mixing wet marl and dry clay, in certain proportions, as a part of the process of manufacturing Portland cement, and by which the various ingredients are thoroughly mixed, and discharged therefrom in a homogeneous mixture, all being continuous, and in a controllable manner, and in which the proportions of the ingredients can be regulated and controlled, and the feed is always regular, even and continuous, according to the "set" of the apparatus.

My invention consists in the novel process and apparatus therefor hereinafter described and which are specifically set forth in the claims hereunto annexed. It is constructed as follows, reference being had to the accompanying drawings, in which

Figure 1, is a sectional elevation of the apparatus, complete. Fig. 2, is a transverse section of the feed-box on line *x*, in Fig. 3. Fig. 3, is a longitudinal section on line *y*, in Fig. 2. Fig. 4 is a side elevation thereof. Fig. 5, is a front elevation.

In this specification I will confine the description of the apparatus to its use in mixing materials for the manufacture of Portland cement, as illustrating the principle of my invention both as to the process and apparatus, it being a fact, that slight and immaterial changes in the apparatus and the application of some of its elements will adapt it to the mixing of the ingredients of other compounds, where the number of such ingredients is greater.

A, is an ordinary pug mill erected substantially horizontal, the means for feeding

the material, wet marl, into it and the mechanism for rotating the shaft—*a*—being omitted as they are of ordinary construction. The 55 shaft—*a*—is provided with flights—*a'*—of ordinary construction and adapted to agitate, pulverize and stir up the marl, and also to feed it longitudinally to the discharge—*a''*—which conducts said marl, still wet, 60 and in a semi-plastic condition, into the brick machine—*B*—, erected upon the support—*B'*—and provided with a vertically erected shaft—*b*—provided with flights—*b'*—which still further stir up, pulverize and disintegrate the wet marl, and also with a lower flight—*b''*—, shown in dotted lines in Fig. 1, which forces the wet marl out through the discharge—*b'''*—. This shaft is driven by the gearing—*c*—actuated by the drive shaft 70—*c'*—mounted in suitable hangers.

From the brick machine the wet marl is discharged into a horizontal or substantially horizontal pug mill—*D*— in a compact and homogeneous bar, said mill being provided 75 with a central shaft—*d*—having flights—*d'*— and is driven by the gearing—*e*—, pulley—*e'*— and belt—*e''*—actuated by the main drive shaft—*c'*—, substantially as shown.

The pug-mill—*A*—and the brick machine 80—*B*—constitute the primary elements of the apparatus, in which the main ingredient is prepared to receive the other, or lesser ingredients in proportion.

E, represents an auxiliary feed-box, supported in a higher plane than the pug-mill—*D*— and adapted to discharge into it, through the same opening through which the marl enters it, after it has been discharged from the brick machine. In making Portland 90 cement, I feed the previously dried and ground clay, through the spout—*f*—into this feed-box. This consists of a substantially vertical sided box, having a hopper shaped bottom—*g*—, provided with a suitable discharge orifice. In the bottom of the box proper, and below the guide-boards—*h*—, which are longitudinal and transverse to said box-body, I mount the feed rollers—*k*—, each provided with the longitudinal V-shaped grooves, as 95 shown, mounted upon central arbors, which are journaled upon said box body and are provided on one end with intermeshing gears—*k'*— which cause both rollers to rotate in-

wardly or toward each other, one of said arbors being driven by means of a pulley —*m*—, belt —*m'*— and pulley —*m''*— on the main drive-shaft —*a'*—. In the feed-box I place a 5 sliding feed regulating partition —*n*— adapted to traverse the box when the screw —*n'*— is operated through the nut —*n''*— secured on the box, by means of the hand wheel, said partition being also provided with guide rods 10 —*p*— secured thereto and adapted to traverse their bearings in the end of the box, said rods also operating to maintain said partition in a vertical position, and one of them being provided with a pointer —*p'*— which is contiguous to the scale-beam —*p''*—, so that the scale thereon will always indicate the distance the partition has traversed the box, or the amount of the box which is open to receive the material, so that, therefore, the feed of the materials through between said rolls is graduated and regulated by the position of said partition, which regulates the engagement of the rolls with the material, and regulates the 15 length of their bite into the material. From 20 this feed-box the dry clay is discharged onto the bar of wet marl, ejected from the brick machine, and the two materials, in their proper proportions, pass into the pug-mill —*D*— where they are thoroughly stirred and mixed 25 together and commingled, and in this condition are discharged from this mill, ready to be made into bricks by any ordinary apparatus and burned and ground in the usual manner: but as these later steps have nothing to do with 30 my invention, I do not show or describe any apparatus either for brick making, burning or grinding after burning; and, therefore, only show and describe as my invention, the apparatus for proportionally mixing the ingredients by a continuous process, and in a 35 controllable manner.

What I claim as my invention, and desire to secure by Letters Patent, is—

1. The combination with the pug-mill, the 40 brick-machine connected to its discharge opening, of the feed-box consisting of a body having a hopper-shaped bottom and the discharge orifice therefrom, longitudinal grooved grinding rollers mounted in said body above 45 the discharge orifice, and adapted to be rotated inwardly, and the vertical partition above said roller, reciprocated longitudinally

to said rollers by a hand screw connected to it and passing through a nut on said body, said brick-machine and feed-box being arranged 55 to commingle their discharge, a second pug-mill receiving said commingled matters, a scale-bar attached to said body, and a pointer-beam mounted upon said partition and passing outward through said body and provided 60 with a pointer upon its outer end, to indicate upon said scale the distance of the longitudinal traverse of the partition.

2. In a mixing apparatus, a feed box consisting of a body having a hopper-shaped bottom and discharge orifice therefrom, longitudinal rollers mounted in the bottom of the body, provided with the V-shaped longitudinal grooves and adapted to be rotated inwardly, and a vertical sliding partition in 70 said body, standing transverse to said rollers, and a hand screw passing through a nut upon said body and centrally connected to said partition, whereby the latter is adjusted longitudinally above said rollers and longitudinally thereto.

3. The combination with the pug-mill, the brick-machine receiving the discharge therefrom of the feed-box provided with feed-rolls having longitudinal V-shaped grooves and 80 adapted to be rotated inwardly, and with a sliding partition transverse to said rollers, and means to adjust it longitudinally in the box to vary the feed of the rollers, and a pug-mill receiving the commingled discharges from 85 said brick-machine and feed-box.

4. The combination with the pug-mill, the brick machine receiving the discharge therefrom, of the feed-box provided with feed-rolls having longitudinal V-shaped grooves and 90 adapted to be rotated inwardly, and with a sliding partition and means to adjust it longitudinally in the box to vary the feed of the rollers, and a pug-mill receiving the commingled discharge from said brick machine and 95 feed-box, a scale and a pointer moved by the traverse of the partition aforesaid, to indicate the feed, from the feed-box.

In witness whereof I have hereunto set my hand this 5th day of April, 1892.

HENRY FROEHLING.

In presence of—

C. W. SMITH,
HOWARD P. DENISON.
